UNITED STATES PATENT OFFICE.

CHARLES A. BRICKLEY, OF PROVIDENCE, RHODE ISLAND.

DESIGN FOR A BRACKET.

SPECIFICATION forming part of Design No. 27,311, dated July 6, 1897.

Application filed May 20, 1897. Serial No. 637,455. Term of patent 3½ years.

To all whom it may concern:

Be it known that I, CHARLES A. BRICKLEY, of the city and county of Providence, in the State of Rhode Island, have invented and produced a new and original Design for Brackets for Towel-Racks, of which the following is a specification, reference being had to the accompanying drawing, which is a perspective view thereof.

- 10 The bracket has a plate A, oblong in shape, with its two long opposite sides parallel for most of its length. The plate terminates near its top and bottom in an inward curve *a* on the edge on both sides, and the ends themselves are semicircular in form, as shown at *b b*. A circular hole or opening *c* is centrally located in each ear. A half-round bead or ridge *d* is on the edge of the plate A throughout its whole extent.
- 15 There are two openings *m m* through the plate A, each having three straight edges and its fourth edge formed in an outward curve or arc, the two curved edges of said openings

being directed toward the center of the plate A.

25 The bracket portion of the design consists of two tongues *n n*, extending at right angles from the face of the plate A. They each have plane surfaces with straight sides and outwardly-curved ends, as shown, and near 30 their ends they each have a circular hole or opening *o*, centrally located within the curve.

What I claim is—

The design for a bracket for a towel-rack herein shown and described, comprising a 35 perforated plate with parallel sides and curved ends, the two tongue-shaped openings *m m*, therein, and the half-round bead or ridge on the edge of the plate throughout its extent, and the two perforated tongues extending from said plate at right angles therewith, substantially as set forth.

CHARLES A. BRICKLEY.
